HENRY LANGE,
INVENTOR,

BY *H. J. Fitz Gerald & Co.*
ATTORNEYS.

UNITED STATES PATENT OFFICE.

HENRY LANGE, OF QUINCY, ILLINOIS.

COMBINATION STOVE LID AND BURNER.

Application filed September 29, 1921. Serial No. 504,012.

To all whom it may concern:

Be it known that I, HENRY LANGE, a citizen of the United States, residing at Quincy, in the county of Adams and State of Illinois, have invented certain new and useful Improvements in Combination Stove Lids and Burners; and I do hereby declare the following to be a full, clear, and exact description of the invention, such as will enable others skilled in the art to which it appertains to make and use the same.

The present invention relates generally to combination coal and gas ranges and stoves, adapted for burning both solid and fluid or gaseous fuels, and the invention relates to a combined lid or cover and burner for a cook stove or range.

It is the object of the invention to provide an extremely simple and efficient lid burner, providing both a removable lid or cover for an opening in the top of the stove or range and a gas burner, for use in burning either coal or other solid fuel and gas, and the construction being easy to manufacture and install and also being compact so as not to require prohibitive or objectional space when applied.

Another object is the provision of such a lid burner which will be substantially flush with the top of the stove or range like the ordinary lid or cover, in combination with a griddle adapted to be used, when burning gas, for supporting the vessel above the lid.

A further object is the provision of a novel member for supplying the gas to the lid burner and adapted to be readily installed in a stove or range under the lid opening for assemblage with the lid burner when placed in the opening.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 is a plan of the device.

Fig. 2 is a section on the line 2—2 of Fig. 1.

Fig. 3 is a bottom plan view of the lid having the burner combined therewith.

Fig. 4 is a plan view of the elbow with which the burner is assembled.

Fig. 5 is an elevation of said elbow.

The present improvements may be used on various kinds of cook stoves and ranges for coal or solid fuel, wherein the stove casing has the top 7 with a lid or cover 8 removably disposed in an opening in said top with its edge disposed in an annular downwardly offset seat 9 surrounding the opening, as well known.

In carrying out the invention, the lid 8 is flat so as to be flush with the top 7 in the usual manner, for supporting vessels placed on the stove when burning solid fuel, and said lid 8 is cast on the under or bottom side centrally thereof with a depending gas chamber 10, which, as shown, is of star formation, having the radial arms 11. The chamber has a central opening 12 for receiving the gas, and that portion of the lid 8 which forms the top of the gas chamber, is provided with gas outlet apertures or holes 13. These holes are arranged in radial rows, as shown, above the arms 11, and it is preferable to form the upper surface of the lid 8 with a groove 14 therein surrounding the holes 13 and of a configuration substantially the same as the chamber 10, thereby giving the central portion of the lid the appearance and form of a gas burner, although same is integral with and flush with the marginal portion of the lid.

The lid 8 has the usual handle socket 15 for convenience in lifting the lid with an ordinary stove lid lifter, and the lid is also cast with an annular depending flange 16 surrounding the gas chamber 10 to strengthen the lid and prevent warping thereof.

In order to supply the burner with gas, an elbow or connecting member 17 is provided, which has one arm extending upwardly and formed with a reduced terminal portion 18 to enter the opening 12 when the lid is placed on the seat 9, as seen in Fig. 2. The other arm of the elbow extends horizontally and receives the inner end of a mixing tube 19 which extends through one wall of the stove casing, and said tube has an air mixer 20 at its outer end for admitting air to mix with the gas that discharges through the valve 21 into the tube 19. The valve 21 is attached to the gas supply pipe 22, which may supply several burners of the stove. The base of the elbow 17 is formed at opposite sides with slotted feet 23 to seat on a horizontal partition 24 in the casing, such as the top of the oven, and the slots can

receive screws, bolts or other securing members for fastening the elbow down on the partition 24, whereby the elbow 17 is firmly held in place.

5 When using gas for cooking, a raised griddle 25 is used in combination with the lid burner, being spaced above the lid, and having feet 26 at its margin to seat on the lid. The lid has depressions or recesses 27 near 10 its edge for receiving the feet 26 of the griddle, and thereby retaining the griddle in place against accidental displacement or sliding movement on the top of the stove. This will also enable the griddle to be properly positioned with respect to the apertures or holes 13, so that the flames do not impinge 15 upwardly against the radial portions of the griddle, and said radial portions of the griddle are therefore in a predetermined relation with the radial rows of holes 13. The cooking vessel is seated on the griddle, when 20 cooking with gas, and when coal or solid fuel is used, the griddle is removed, thereby leaving the top of the stove unobstructed 25 and flush, the same as with an ordinary lid or cover.

Having thus described the invention, what is claimed as new:—

1. A flat stove lid having a depending integral gas chamber spaced from the margin 30 of the lid, said chamber having a lower cen-

tral inlet opening to fit over a gas supply member, and said lid having gas outlet holes above said chamber.

2. A stove lid having a depending gas 35 chamber and gas outlet holes above said chamber, said lid having a depending flange surrounding said chamber.

3. A device of the character described comprising a stove having a gas chamber 40 and radial rows of gas outlet holes above said chamber, and a griddle having feet to rest on said lid, the lid having portions for receiving said feet to position the griddle in a predetermined relation with said holes. 45

4. A device of the character described comprising a flat stove lid having a depending gas chamber and radial rows of gas outlet holes above said chamber, and a griddle having feet to rest on said lid, and having radial 50 portions, said lid having recesses for receiving said feet to position said radial portions of the griddle in a predetermined relation with reference to said holes.

In testimony whereof I have signed my 55 name to this specification in the presence of two subscribing witnesses.

HENRY LANGE.
